(57) **CLAIM**

The ornamental design for a ceiling fan with halo light as shown and described.

DESCRIPTION

FIG. 1 is an elevated, front perspective view of the new design for a ceiling fan with halo light;

FIG. 2 is a lowered, front perspective view of the design of FIG. 1;

FIG. 3 is a top plan view of the design of FIG. 1;

FIG. 4 is a bottom plan view of the design of FIG. 1;

FIG. 5 is a front elevational view of the design of FIG. 1, the rear elevational view being the mirror image thereof;

FIG. 6 is a left side elevational view of the design of FIG. 1; and,

FIG. 7 is a right side elevational view of the design of FIG. 1.

Broken lines included within the drawings (FIGS. 1, 3) depict environmental subject matter only and form no part of the claimed design.

The stippling in the drawings depict contrast in appearance.
